W. J. DAWSON

PORTRABLE DRILLING MACHINE

Filed Jan. 28, 1925

Fig. 1.

Fig. 2.

UNITED STATES PATENT OFFICE.

WILLIAM J. DAWSON, OF COLLBRAN, COLORADO.

PORTABLE DRILLING MACHINE.

Application filed January 28, 1925. Serial No. 5278.

To all whom it may concern:

Be it known that I, WILLIAM J. DAWSON, a citizen of the United States, residing at Collbran, in the county of Mesa and State 5 of Colorado, have invented certain new and useful Improvements in Portable Drilling Machines, of which the following is a specification.

My invention relates to improvements in 10 portable drilling machines, and more particularly to that type known as feed drills. The machine, in operation, eliminates the usual manual application of pressure and manual support requisite of the present 15 makes of portable drills now commonly in use, and commonly found on the market.

An important object of the present invention is to provide a drill that will automatically feed the bit toward the work as the 20 shaft of the drill is being rotated.

Another important object of the invention is to provide means whereby the bit may be fed toward the work independently of the rotation of the shaft.

Another object of the invention is to provide a drill that may be attached to the work in a manner so as to dispense with the usual 25 manual exertion, incident to machines of this nature now in common use.

A still further very important object of the invention is to generally improve upon portable drills, by providing a structure which, while strong and durable is, at the same 30 time, light and capable of being easily handled, and wherein all parts are accessible for repair and constantly in open view for inspection, one which is thoroughly reliable in operation, inexpensive to manufacture, not liable to readily get out of order, and well 35 adapted to the purpose for which it is designed.

With the above and numerous other objects in view, as will appear as the description proceeds, the invention resides in certain 40 novel features of construction, and in the combination and arrangement of parts as will be hereinafter more fully described and claimed.

In the drawing:

Figure 1 is a side elevation of my improved apparatus, with parts thereof in section.

Figure 2 is an enlarged detail perspective view of the bit retaining feature.

Referring to the drawing in detail, it will be seen that 1 denotes a frame comprising

two or more parallel strips preferably of a light metal, internally connected at one end by an internally threaded annulus 2, and at their opposite ends by a plate 3. An externally threaded elongated sleeve 3' is threaded through the internally threaded annulus 2, and is provided with a head 4, for the purpose of carrying a pivoted lever 5. A crank arm 6, having a knob 7, is employed to actuate a shaft journaled through a sleeve 3'. A bit receiving shank 9 fits over the extremity of the shaft 8, and is secured thereto by a set screw 10. A pin 11 extends through the bit receiving shank 9 and carries at each end the respective extremity of the U-shaped bracket 12. This pin is provided intermediate its ends with a notch 15, conforming in shape to the bit head shapes of standard makes. A notch 13 is provided in one side edge of the intermediate portion of the bracket 12, for the purpose of receiving the shank of the bit 14, under the head thereof, and tends to retain this bit in proper engagement with the bit receiving shank 9, 80 since the engagement of the head of the bit with the pin 11 at its notch 15 tends to prevent rotation of the pin, thereby tending to prevent the intermediate portion of the bracket 12 from swinging away from the 85 shank of the bit 14. When the bracket 12 is manually swung away from the bit 14, the rotation of the pin caused thereby tends to push the head of the bit out of the bit receiving shank 9. A washer 16 spaces the 90 bit receiving shank from frictional contact with a reciprocatory guide block 17, carried by the shaft 8, and in which the shaft 8 is free to rotate. This block is grooved, at its periphery for receiving the strips of the 95 frame 1, thereby acting as a guide for the shaft and the bit associated therewith. A flanged collar 18 is secured to the shaft 8, and is rotatable therewith. A plurality of washers are supported on the flanged side 100 of the collar 18, as at 19, to separate this flanged collar, from direct frictional engagement with the threaded sleeve 3, and thereby providing added bearing surfaces 105 that will prevent the destructive wear of major parts of the apparatus.

It will be seen that when the lever 5 is swung from the position shown in Figure 1, over toward the shaft 8, it will rest in the path of the crank 6, and as this crank 110 is rotated, it will engage the lever 5, causing the rotation of the sleeve 3' with the

shaft, thus feeding the bit toward the work while it is being rotated. When the lever 5 is disposed, as shown in Figure 1, the sleeve 3 may be rotated independently of 5 the shaft 8, and the bit fed toward the work independently of the rotation of the shaft 8, as may be desired. The bit 14 is adapted to be fed through a bit guide 20, which is retained in position by a pin 21, which projects through the frame strips and extends 10 into the surface of the bit guide being held in place by springs 22.

A link 24 loosely connects a turn buckle 25 and fastener 26 to one end of the plate 15 3, and a chain 27 is engaged with the other end of the plate, so that it may be disposed about the object to be worked upon and engaged with the fastener 26, in order that the plate is held in proper position thereon. It 20 will be apparent from the above that I have devised a very simple and efficient portable drill apparatus, which embodies the features of advantage enumerated as desirable in the statement of the invention 25 and the above description, and that numerous changes may be made in the details of construction, materials, and in the combination and arrangement of parts without de-

parting from the spirit or scope of the invention as hereinafter claimed, or sacrificing 30 any of its advantages.

Having thus described my invention, what I claim as new is:

A portable drill of the character described comprising a frame, a sleeve threadedly mounted in the frame and provided with an enlarged head at its outer-extremity, a shaft rotatably mounted in the sleeve and provided with a bit receiving socket at one end, and an offset portion at its other end, 35 a lever pivoted to the enlarged head on the sleeve and adapted to interlock with the offset portion of the shaft for causing a simultaneous rotation, and feeding of the shaft in respect to the frame, a guide block slideable in the frame, said frame being provided with a pair of guides engageable by said block, said shaft passing through said guide block, a collar on the shaft engageable with said guide block, and holding the same in 40 engagement with the bit receiving socket end, the inner end of said sleeve adapted to abut said collar.

In testimony whereof I affix my signature.

WILLIAM J. DAWSON.
